UNITED STATES PATENT OFFICE.

JAMES CAREY DAVIS, OF HINSDALE, ILLINOIS.

MOLD.

1,161,034.

Specification of Letters Patent. Patented Nov. 23, 1915.

Application filed February 21, 1911. Serial No. 610,015.

To all whom it may concern:

Be it known that I, JAMES CAREY DAVIS, a citizen of the United States, and a resident of Hinsdale, in the county of DuPage and State of Illinois, have invented certain new and useful Improvements in Molds, of which the following is a specification.

My present invention relates to molds useful in the art of casting metal in general, 10 more particularly to metallic molds, and especially to the provision of improved means whereby a casting of uninterrupted periphery, and free from cracks may be produced in an iron mold.

15 The principal objects of my present invention are the provision of an improved form of mold, and more particularly, an iron mold, which I find in practice generally useful in the casting of bodies having 20 relatively large centers and peripheral portions and relatively thin intermediate portions, and specially useful when such bodies are made of cast steel which has a tendency to crack peripherally when cast in metal 25 molds, such molds being especially desirable for the production of cast steel wheels and like structures wherein not only tread 30 cracks, but also flange cracks, as well as fractures in the surface are particularly to 35 be avoided; together with such further objects as will hereinafter appear.

In the production of cast steel wheels and other structures by apparatus and processes heretofore known to me I have experienced 35 great difficulty in utilizing iron molds having circular or rounded portions or relatively thin portions for the production of steel castings, owing to the tendency of the steel to cool so rapidly that cracks develop 40 on such circular or rounded portions or in such relatively thin portions.

In accomplishing the foregoing objects, and overcoming the disadvantages referred to, and in attaining certain further benefits 45 to be below disclosed, I have provided the constructions illustrated in preferred form in the accompanying drawings, wherein—

Figure 1 is an elevational view, partly in vertical section, of a mold embodying my 50 invention; Figs. 2 and 3 are respectively under and top plan views of the cope of the mold of Fig. 1; Fig. 4 is a top plan view of a drag used in forming of the mold of Fig. 1, and Fig. 5 is an under plan view of the

cheek ring used in connection with the mold 55 of Fig. 1.

Referring now more particularly to Fig. 1 it will be observed that I have here illustrated a form of mold comprising a cope 1, a drag 2 and an intermediate cheek piece 3 60 which I find specially useful in carrying out my invention, a wheel being here indicated for purposes of convenience, the center, tread, and corrugated flange being respectively indicated at 4, 5 and 6, and the cope 2 being gated at 7 and provided with a sand core as indicated at 8, sand cores also being provided at 9 and 10 to allow the formation of narrow necked risers which may be readily broken away. In pouring such structures in an ordinary mold I have found that the tread 5 cracks transversely, but that by providing the cheek ring 3 with sand inserts 11—11 arranged at intervals transversely of the tread I have found that the wheel cools 70 more slowly and without surface cracks in such tread, though the other advantages of the use of an iron mold remain.

In using iron cope and drag members in the usual manner, or even in connection 80 with the improved form of cheek piece 3 with sand inserts I have found that the web cracks radially, especially at the highest and lowest points of the corrugations, indicated at 12 and 13 respectively, but that by 85 providing the upper surface of the drag and the lower surface of the cope with sand inserts, radially disposed as indicated at 14 and 15 respectively and alternating their position as indicated in Fig. 3, I 90 am enabled to produce a wheel having a web free from all cracks whatever, whether used in connection with the said inserts 11, or otherwise, and that by using the combination of inserts 11, 14 and 15 in the manner hereinabove disclosed, I am enabled to 95 produce in an iron mold a steel wheel entirely free from cracks.

While I have illustrated my invention in connection with a mold available for the 100 manufacture of wheels, and believe that it is particularly useful for the production of such articles and others wherein it is especially desirable to have freedom from cracks my invention is obviously useful in the 105 manufacture of other castings.

It is believed that the operation of my invention will be understood without fur-

ther detail description, and that other advantages of my invention and other specific means of employing it will occur to those who are skilled in the art to which my invention pertains.

Having thus described my invention and illustrated its use, what I claim as new and desire to secure by Letters Patent is the following:

- 10 1. In a casting apparatus, a mold comprising metal cope and drag portions, one thereof having a curved or rounded surface provided with a plurality of spaced sand inserts extending transversely of such curved or rounded surface substantially the width of said surface.
- 15 2. In a casting apparatus, a metal wheel mold having fluted or corrugated surfaces for the web of the wheel provided with sand inserts substantially coincident with said fluted or corrugated portions.
- 20 3. In a casting apparatus, a metal wheel mold having radially fluted or corrugated surfaces for the web of the wheel provided with sand inserts substantially coincident with said radially fluted or corrugated portions.
- 25 4. In a casting apparatus, a mold comprising metal cope and drag portions, one provided with a cheek portion having a substantially rounded inner periphery provided with spaced sand inserts extending transversely of such periphery.
- 30 5. In a casting apparatus, a car wheel mold comprising metal cope and drag portions each provided with radially arranged sand inserts.
- 35 6. In a casting apparatus, a car wheel mold comprising metal cope and drag portions each provided with radially arranged sand inserts, the inserts in the cope being arranged in alternation with those in the drag.
- 40 7. In a casting apparatus, a car wheel mold comprising a cope, a drag, and a cheek portion, said cope and drag being provided with radially arranged sand inserts, and said cheek portion with transversely arranged sand inserts.
- 45 8. In a casting apparatus, a car wheel

mold comprising a cope, a drag, and a cheek portion, said cope and drag being provided with radially arranged sand inserts, and said cheek portion with sand inserts.

9. In a casting apparatus, a car wheel 55 mold comprising a cope, a drag, and a cheek portion forming a mold cavity, said cope and drag being provided with sand inserts extending from adjacent the periphery of the mold cavity toward the center thereof, 60 and said cheek portion being provided with sand inserts.

10. In a casting apparatus, a car wheel mold comprising a cope and a drag forming a mold cavity, said cope and drag being provided with sand inserts extending from adjacent the periphery of the mold cavity toward the center thereof. 65

11. In a casting apparatus, a car wheel mold comprising a cope, a drag, and a cheek 70 portion forming a mold cavity, said cope and drag being provided with sand inserts extending from adjacent the periphery of the mold cavity toward the center thereof and said cheek portion being provided with 75 said inserts arranged transversely thereof.

12. In a casting apparatus a mold having a curved or rounded surface of metal, and an exposed metal surface arranged at an angle thereto, said first mentioned surface 80 being provided with a plurality of spaced sand inserts severally extending transversely thereof substantially the width of said surface.

13. In a casting apparatus a mold having 85 a curved or rounded surface of metal, and an exposed metal surface arranged at an angle thereto, said last mentioned surface being provided with a plurality of spaced sand inserts severally extending transversely thereof substantially the width of said surface. 90

In testimony whereof I have hereunto signed my name in the presence of the two subscribed witnesses.

JAMES CAREY DAVIS.
